PLASTIC CURTAIN MATERIAL

Elmer P. Scott, New York, N.Y.

Application July 10, 1958, Serial No. 51,732

Term of patent 7 years

(Cl. D87—3)

The figure is a plan view of a plastic curtain material showing my new design on a dark background so as to bring out more clearly the details thereof, a full width being shown and the pattern repeating in a horizontal direction.

I claim:

The ornamental design for a plastic curtain material, as shown and described.
